UNITED STATES PATENT OFFICE.

NATHAN MORSE, OF AKRON, OHIO.

JAR-HOLDER.

SPECIFICATION forming part of Letters Patent No. 276,064, dated April 17, 1883.

Application filed October 25, 1882. (No model.)

To all whom it may concern:

Be it known that I, NATHAN MORSE, of Akron, in the county of Summit and State of Ohio, have invented a new and useful Improvement in Jar-Holders, (which has not been patented to myself, nor to others with my knowledge and consent, in any foreign country, and which, according to my knowledge and belief, has not been in public use in the United States for more than two years prior to this application,) of which the following is a specification.

My invention relates to that class of jar-holders that are used to remove such can-tops as are screwed on.

The object of my invention is to provide a simple, cheap, and effectual clamp by which such can-tops may be easily removed or replaced.

My invention consists in the device illustrated in the accompanying drawings, in which Figure 1 is a plan of my improved jar-holder, and Fig. 2 an inside elevation of one half and a section at the line *xx*.

In the drawings, A is a metallic spring-band, 25 continued and terminating at either end in

handles *aa*, and provided on its inner surface with a channel, in which is placed a frictional band, B, of felt, rubber, or other material. The diameter of this band, when not compressed, should slightly exceed that of the can-top to be removed, so that by causing the handles *aa* to approach each other it will grasp and firmly hold the can-top. 30

I claim as my invention—

In a jar-holder, the combination, with the metallic spring A, provided with handles *aa*, formed in one piece with the said spring, and channelled or grooved upon its inner surface, as shown, of the band B, of rubber or other suitable material, seated in said groove or channel, substantially as described, and for the purpose specified. 35 40

In testimony that I claim the foregoing I have hereunto set my hand this 21st day of October, A. D. 1882.

NATHAN MORSE.
